HOLDER FOR PENCILS, PAPERS, AND THE LIKE

Melvin K. Bolling, 2nd Ave., Holland, Ind. 47541

Filed July 30, 1971, Ser. No. 167,891

Term of patent 14 years

Int. Cl. D19—02

U.S. Cl. D74—5 A

FIG. 1 is a front perspective view of a holder for pencils, papers, and the like, showing my new design;

FIG. 2 is a top plan view thereof;

FIG. 3 is a rear elevational view; and

FIG. 4 is a left side elevational view thereof.

I claim:

The ornamental design for a holder for pencils, papers, and the like, as shown.
